UNITED STATES PATENT OFFICE.

HIRAM D. BENJAMIN, OF DE RUYTER, NEW YORK.

DESIGN FOR WOOD MOLDING.

SPECIFICATION forming part of Design No. 11,785, dated May 18, 1880.

Application filed March 8, 1880. Term of patent 14 years.

To all whom it may concern:

Be it known that I, HIRAM D. BENJAMIN, of De Ruyter, in the county of Madison and State of New York, have invented a new and Improved Design for Wood Molding, of which the following is a specification.

This design is applicable to moldings for every description of wood-work where carving is employed, such as picture-frames, door and window frames, wainscoating, and various other portions of the inside or outside of a house, also furniture and other articles, and is adapted to either flat, convex, or concave surfaces.

The design consists, essentially, in curved grooves with their concave sides toward each other, so as to form an approximation to a semi-elliptical figure, and having elliptical or oval concavities between.

The accompanying drawings illustrate modes of carrying out the design.

Figure 1 represents a strip of wood with the grooves and cavities arranged in groups occupying certain positions with relation to each other. Fig. 2 represents another strip of wood having the groups in relative positions different from those shown in Fig. 1, and also of different sizes.

These two figures are deemed sufficient for illustration.

Each figure of the design consists of two curved grooves, A A, each forming an approximation to a semi-ellipse; but the ends nearest each other do not quite meet, and therefore the semi-ellipse is not complete. Between the grooves there are three oval concavities, B and b b, the largest oval B in the narrowest portion of the space between the grooves and the two smaller ones b b in the widest portion of said space and on either side of B. These two grooves and three ovals form

what I here designate as a "figure" of the design. These figures may be arranged side by side to form what I designate as a "group." In such case there may be one or more oval or approximate oval concavities, C c, between every two figures. These figures and groups may be further arranged one above another, in which case the groups have a straight groove, D, between them.

In Fig. 1 the figures and groups are arranged with the widest portion of each figure opposite the widest portion of the figure below it, so that the four grooves A would form an ellipse but for the interruption by the straight groove D and the abrupt termination of the grooves. The left-hand end of Fig. 1 illustrates how the figure may be arranged on a curved instead of a straight line.

In Fig. 2 of the drawings three groups are shown, the upper one having the figure nearly double the size of the figure in the two groups below it, and each group having a straight groove, D, under it. In the two lower groups the figures are arranged so that the narrowest portion of one figure is opposite the widest portion of the figure immediately over it.

The grooves and concavities above described may be formed either with hand tools or by machinery arranged for the purpose.

Having thus described my design, what I claim as new, and desire to secure, is—

In a design for wood molding, a figure composed of two curved grooves with their concave sides toward each other, and having oval or ellipsoidal concavities between them, as herein shown and described.

HIRAM D. BENJAMIN.
